UNITED STATES PATENT OFFICE.

CHARLES W. DAKE, OF GRAND RAPIDS, MICHIGAN.

ELASTIC-FLUID TURBINE.

No. 858,500.

Specification of Letters Patent.

Patented July 2, 1907.

Application filed September 4, 1906. Serial No. 383,267.

To all whom it may concern:

Be it known that I, CHARLES W. DAKE, a citizen of the United States, residing at the city of Grand Rapids, county of Kent, and State of Michigan, have invented 5 certain new and useful Improvements in Elastic-Fluid Turbines, of which the following is a specification.

This invention relates to improvements in elastic fluid turbines.

Heretofore, as turbines have usually been constructed, the jet of fluid delivered from the nozzle is projected different distances into the buckets of the turbine and, owing to the consequent unequal distribution, part of the effectiveness of the flow of the fluid is lost, because part of it acts too soon, and part of it not soon enough 15 against the walls of the vanes or buckets. It is also desirable to confine the space within the vane buckets to secure the most effective action when completed.

It is the object of this invention, first, to provide an improved construction of turbines in which the fluid is 20 delivered most effectively into the buckets. Second, to provide an improved construction and arrangement of the parts for avoiding eddy currents within the buckets.

Further objects, and objects relating to structural details, will definitely appear from the detailed description to follow.

I accomplish the objects of my invention by the devices and means described in the following specification.

30 The invention is clearly defined and pointed out in the claims.

A structure embodying the features of my invention is clearly illustrated in the accompanying drawing forming a part of this specification in which,

35 Figure 1 is a detailed sectional view showing the former arrangement of nozzles and buckets of the U-shaped form. Fig. 2 is a detailed sectional view of my invention as used with the full recurve U-shaped bucket.

Fig. 3 is a detailed sectional view of my invention as 40 used with U-shaped buckets forming a part of my application for patent filed the 22nd day of March, 1906, Serial No. 307,457. Fig. 4 is a detailed sectional view taken on the irregular line X—X of Fig. 2, showing the stepped form of buckets 2. Fig. 5 is a detailed sectional

45 view of my invention as used with U-shaped buckets, the walls of which are but partly cut out or reduced. Fig. 6 is a sectional view showing a modification of my invention, the form of the mouth of the nozzle being shown on right angle lines. Fig. 7 is a detailed sectional view of my invention as used with double U-shaped buckets.

In the drawings, similar numerals of reference refer to similar parts throughout the several views.

Referring to the numbered parts of the drawing, the 55 turbine wheel 1 is of a usual form having the buckets formed on its periphery. The buckets 2 are of the U-

shaped recurved type. The buckets may be on the periphery of the wheel or element or they may be on the side of the same. The buckets are shown on the side in Figs. 2 and 6.

The nozzle 3 is formed on a nozzle block 7 for delivering the elastic fluid to the turbine buckets and a discharge opening or clearance 4 is on the opposite side of the block 3. The block 3 may be a complete ring or it may be made in sections or be a partial ring. The nozzle has a short side at 5 and a longer side at 6, the longer side projecting well down into the bucket, and the block has a projection 7 which extends down well toward the bottom of the bucket to form a comparatively narrow space in the bottom thereof. The bucket is 60 notched or cut down at 8 to accommodate the projection 7.

The exit passage at 4 is considerably larger than the nozzle. This formation of the block and bucket is best secured by forming an annular groove in the turbine 75 which cuts away the central part of the division walls between the buckets and allows the side walls of the same to project. The exit 4 can be turned back substantially parallel with the nozzle 3, or, in certain types, can deliver out at the side of the turbine as appears most clearly in Fig. 3.

The preferred form of the bucket and nozzle blocks appears in Fig. 2, where the annular groove and the projecting part are curved. Substantially the same result, however, would be accomplished by an angular formation as appears in Fig. 5, where the parts are beveled or by a right-angled construction, as appears in Fig. 6.

In Fig. 7 I show a double construction with the exhaust out at the sides of the buckets. This has some advantage in that it increases the area for the action of 90 the steam or elastic fluid when a simple turbine is employed in place of a compound. This double construction also secures a perfectly balanced turbine, there being no thrust produced.

In Fig. 1, as illustrated, what might be called an ordinary arrangement of the buckets and nozzle, without the oblique opening to the nozzle, is shown and it will there be seen that the steam or fluid entering the buckets from that nozzle will have to travel much farther from the point of the nozzle on the inner side before it 95 acts than it does on the outer side, and this affords opportunity for eddy currents to form and greatly interferes with the efficiency of the turbine. The nozzle 3 there delivers straight in presenting different velocity and expansions from the same nozzle in the recurved 100 buckets and, as the nozzle block does not project down into the bucket, there is a chance for the formation of eddy currents within the bucket itself, otherwise a considerable volume of steam is lost and the efficiency of the turbine interfered with.

110 In my invention, both sides of the nozzle 3 are almost of equal distance from the curved wall of the

bucket 2 in the direction of the flow of the fluid, and consequently the fluid will impact the curved wall of the bucket 2 with almost equal force at all points from the mouth of the nozzle, and also by reason of this there 5 can be no eddy currents, as with the old form of bucket and nozzle, because the nozzle 3 delivers the fluid nearer to the curved wall of the bucket 2 and also by reason of the ring or projection 7 extending into the scallop or grooves in the side walls of the bucket, 10 thus confining the fluid more closely to the curved walls of the said buckets. The passage of the fluid through the nozzle, bucket and exit passage is clearly shown by the arrows therein.

Having thus described my invention, what I claim 15 as new and desire to secure by Letters Patent is:

1. In an elastic fluid turbine engine, the combination of a turbine wheel with buckets of the U-shaped type in the periphery thereof, having an annular groove cut through the buckets so that the separating walls of the 20 buckets are reduced in height; and a nozzle and passage block with projections entering the annular groove formed in the said buckets, the nozzle being formed in the block with a long and short side, the longer side projecting towards the bottom of the buckets, coacting for the purpose specified.
2. In an elastic fluid turbine engine, the combination of a turbine wheel with buckets of the U-shaped type therein, having an annular groove cut through the buckets so that the separating walls of the buckets are reduced 25 in height; and a nozzle and passage block with projec-

tions entering the annular groove formed in the said buckets, the nozzle being formed in the block with a long and short side, the longer side projecting towards the bottom of the buckets, coacting for the purpose specified.

3. In an elastic fluid turbine, a turbine wheel or rotatable element; U-shaped buckets; and a nozzle to deliver fluid to the buckets, said nozzle having its side nearest to the center of the buckets extending beyond its outer side in the direction of the fluid flow, coacting for the purpose specified. 35

4. In an elastic fluid turbine, a turbine wheel or rotatable element 1; a U-shaped bucket 2; a nozzle having a short wall 5 and an extending wall 6; a reduced space 8; and a projection 6, coacting for the purpose specified. 40

5. In an elastic fluid turbine, a rotatable element 1; 45 and buckets 2, in combination with a nozzle 3, having an extended wall 6, arranged within a groove through the bucket walls coacting for the purpose specified.

6. In an elastic fluid turbine, a rotatable element; and a nozzle for delivering fluid to the rotatable element, said 50 nozzle having one side extended into a groove in the rotatable element, for the purpose specified.

7. In an elastic fluid turbine, a turbine wheel having U-shaped buckets; and a nozzle formed to deliver a jet of fluid later from its side nearest the center of the bucket 55 than at its side farthest therefrom, for the purpose specified.

In witness whereof, I have hereunto set my hand and seal in the presence of two witnesses.

CHARLES W. DAKE. [L. S.]
